UNITED STATES PATENT OFFICE

110,976

DESIGN FOR A FLORAL DISPLAY STAND

Robert A. Norton, Chatham, N. J.

Application March 18, 1938, Serial No. 75,931

Term of patent 3½ years

To all whom it may concern:

Be it known that I, Robert A. Norton, a citizen of the United States of America, residing in the city of Chatham, State of New Jersey, have invented a new, original, and ornamental Design for a Floral Display Stand, of which the following is a specification, reference being had to the accompanying drawing, forming part thereof, wherein,

I claim:

The ornamental design for a floral display stand, substantially as shown.

ROBERT A. NORTON.
